L. SCHOLLER

NECKTIE HOLDER

Filed June 15, 1923

FIG. 1

FIG. 2

FIG. 3

FIG. 4

Louis Scholler
INVENTOR

BY Harry Cohen
ATTORNEY

UNITED STATES PATENT OFFICE.

LOUIS SCHOLLER, OF SAN FRANCISCO, CALIFORNIA.

NECKTIE HOLDER.

Application filed June 15, 1923. Serial No. 645,577.

To all whom it may concern:

Be it known that I, LOUIS SCHOLLER, a citizen of the United States, residing in the city and county of San Francisco, in the State of California, have invented a certain new and useful Necktie Holder, of which the following is a specification.

This invention relates to a necktie holder and more particularly to a holder for a necktie of the four-in-hand type, and has for its main object the provision of a holder that is invisible when in use.

Another object of the invention is to provide a holder that will keep the tie in position without making a tight knot.

A further object of the invention is to provide a necktie holder that will preserve the tie and prevent same from becoming unduly wrinkled.

These and other objects are attained by the provision of the device constituting the necktie holder which will be hereinafter described in detail, reference being had to the accompanying drawings in which:

Fig. 1 is a side elevation of the necktie holder, before being placed in the shirt front;

Fig. 2 is a front elevation of the necktie holder in the position shown by Fig. 1;

Fig. 3 is a front elevation of the necktie holder as it appears when placed in the shirt front; and

Fig. 4 is a view showing the holder in position in the shirt front in relation to the tie when in use.

Referring to the drawings in detail, the holder comprises the telescoping members 1 and 2, the member 1 being of hollow tubular construction and the member 2 being a rod of circular cross section. The rod 2 is in sliding engagement with the tubular member 2 and is pressed outwardly therefrom by a compression coiled spring 3 one end of which is attached to the rod 2 and the other end of which is attached to the cap 4 which is mounted on the upper end of the tubular member 1. The cap 4 is provided with the prongs 5 which serve to engage the tie near or at the knot thereof as will be

clearly apparent more particularly from Fig. 4 of the drawings.

The rod 2 is provided at its lower end with an outwardly curved portion 6 on which is mounted a stud or button 7 adapted to be placed in a button hole of the shirt front, as is obvious.

The construction of the holder is believed to be clear from the above description and the manner of use is also thought to be so obvious as to make further explanation unnecessary. It will be understood that the tie is held in place by the tension imparted to the cap 4 and the attached prongs 5 which engage the tie, the stud 7 being positioned in a buttonhole which thereby supports the entire holder. The advantages of the device are believed to be apparent and the objects of the invention, as above enumerated, are believed to be realized by the embodiment illustrated and described. And while I have shown and described the preferred embodiment of the invention, it is to be understood that certain changes in the arrangement and construction of parts may be made without departing from the invention as defined by the appended claims.

Having thus described my invention, what I claim and desire to secure by Letters Patent of the United States is:

1. A necktie holder comprising two spring pressed telescopic members, one of said members having a stud adapted to be inserted within a button hole in the front of the shirt of the wearer and the other of said members having means to engage the necktie to thereby support it in proper adjusted position.

2. A necktie supporter comprising two members and spring means yieldingly urging said members apart, one of said members having a stud adapted to be received within the button hole in the front of the shirt of the wearer, and the other of said members being adapted to engage the necktie to thereby support it in proper adjusted position.

3. A necktie holder comprising means to engage the front of the shirt of the wearer, means adapted to engage the necktie at a

point above that at which the shirt is engaged whereby the necktie is held in proper adjusted position, and means for yieldingly urging apart said shirt engaging means and said necktie engaging means.

4. A necktie holder comprising two telescopic members and spring means yieldingly urging said members apart, one of said members having means to engage the shirt

front of the wearer, and the other of said members having prongs for engaging the necktie at a point above that at which the shirt front is engaged whereby the necktie is supported in proper adjusted position.

In witness whereof, I hereunto affix my ¹⁵ signature.

LOUIS SCHOLLER.
